UNITED STATES PATENT OFFICE.

ROBERT W. SCOTT, OF BOSTON, MASSACHUSETTS, ASSIGNOR TO SCOTT & WILLIAMS,
INCORPORATED, OF BOSTON, MASSACHUSETTS, A CORPORATION OF NEW JERSEY.

WELTED KNIT FABRIC AND METHOD OF MAKING THE SAME.

1,113,166.

Specification of Letters Patent.

Patented Oct. 6, 1914.

Application filed March 7, 1914. Serial No. 823,121.

To all whom it may concern:

Be it known that I, ROBERT W. SCOTT, a citizen of the United States, and resident of Boston, in the county of Suffolk and State 5 of Massachusetts, have invented certain new and useful Improvements in Welted Knit Fabrics and Methods of Making the Same, of which the following is a specification.

My invention relates to knit fabrics having 10 welts or hems and especially to plain knit articles having outturned welts of the general character illustrated in my Patents 1,045,620, November 26, 1912 and 1,079,267, November 18, 1913, and to the art of making 15 such fabrics.

One object of my invention is to provide a welt for an article of this class having a texture like that of the attached fabric and a juncture or union between the welt proper 20 and the attached fabric of improved appearance and durability, which can be made by simple steps, such as can be practised by hand operated or automatic machinery.

Figure 1 is a side view of a stocking illustrating one type of my improved article; Fig. 2 is a diagram illustrating steps of the method as practised on one type of circular machine; Fig. 3 is a diagram of the front or face side of the fabric at the juncture of 30 the welt; Fig. 4 is a view like Fig. 3 showing a modification; Fig. 5 is a section through a wale *a* of Fig. 3.

My improved article may be composed of flat or tubular fabric having therein needle 35 wales *a* and *b*, separated by the usual sinker-wales. For one instance, I may provide an integral welt *W* and top *T* for a circular knit or seamless stocking as shown in Fig. 1, having a leg *L* and foot *F*, and a heel and toe of 40 usual form, the leg *L* consisting of fabric of any desired number of needle-wales in width, the top *T* having therein fewer needle-wales, and the welt *W* having as many needle wales as the top.

My new article is of the genus illustrated 45 by my said patents, comprising plain fabric having a welt or welts of which the back or loop side is outward, the face or wale side lying within a tubular fold continuous with 50 that part of the article to which it is attached, certain loops at or near the beginning of the welt being withheld upon the needles, and subsequently attached where the welt fabric joins the article, by loops engaging the withheld loops, a course of such 55

loops being hereinafter referred to as a uniting course. One form of the welt of the earlier Patent No. 1,045,620 has as many wales as the attached part of the article, the withheld loops for uniting the beginning of 60 the welt being the initial loops of all the needle wales of the welt, which wales are continuous with needle wales of the body fabric. My later Patent #1,079,267 disclosed an article having withheld uniting 65 loops occurring neither in the needle wales of the welt fabric nor the initial course thereof, but in sinker wales of the welt fabric corresponding to recurrent needles inoperative during knitting of the welt, said recurrent needles again operating together 70 with the needles employed for the welt, to knit the uniting course and the attached part of the article, so that the needle wales of the welt were all continuous with needle wales 75 of attached fabric having therein as many more wales as there were withheld or uniting loops.

Referring now to Fig. 3 I retain the advantages of both of said patented constructions by providing a welt *W* having as many needle wales *a* as the attached fabric *T* has wales *b*, the withheld loops *w* being provided in needle wales corresponding to the wales *b* of fabric *T*, which wales *b* stand between and correspond to the sinker-wales 80 between wales *a* of the welt fabric *W*. The withheld loops *w* are engaged and attached to the wales *b* of the fabric *T* by a uniting course *Z* having initial loops *z* penetrating 85 the loops *w* in all of the wales *b* and having loops *y* in all of the wales *a*. The loops *y* of the course *Z* engage the final course as 90 of the welt fabric, which consists of needle loops in the wales *a* only, corresponding to 95 the sinker-wales between the loops in the wales *b* of the fabric *T*.

In order to prevent the lateral strain upon the uniting course *Z* from withdrawing the loops *y* from engagement with the last 100 course, such as 28, of the welt fabric in the wales *a* I may provide in the wales *a* a course *x'* of locking loops, which may be thrust forward into engagement with the fabric *T*. The course *x'* may be followed by a similar course *x''*. Said courses *x'* and *x''* together 105 constitute a strip of locking fabric *X*, projecting from the juncture formed by the uniting course *Z* on the inside or back of the fabric, for instance within the tubular top 110

of the illustrative seamless stocking, the free end loops of said locking fabric being under frictional restraint by reason of their passage through the sinker-wales of subsequently formed courses of fabric T.

The structure of the first few courses 1, 2, 3, 4, etc. of the welt may be substantially that shown in my said Patent 1,079,267, comprising for instance a course 1 taken by 10 the needles employed to knit the wales *a* and passing at the back of the needles employed to knit the wales *b*; a course 2 taken by the needles A and B employed to knit the wales *a* and *b*, the needles B for the 15 wales *b* retiring at this point in the operation to withhold the loops *w*, during the knitting of courses 3, 4, etc. of sufficient fabric for the welt upon the needles A only, the sinker wales of said fabric knit upon 20 the needles A passing over the heads of the needles B during such times as the loops *w* are to be withheld. It is obvious that the welt may be begun in any manner, so long as a course from which loops *w* may be withheld is provided. This course, for instance, 25 may be as shown the second course of fabric beginning at a selvage 1, or it may be any course in an extent of fabric the previous part of which will afterward be cut or 30 raveled away and removed.

The welt fabric may extend for any desired number of courses, for instance to include sufficient courses to form a welt W of the proportions shown in Fig. 1 or until 35 course 28 is reached, when the welt will be completed by knitting the uniting course Z upon all the needles A and all the needles B to connect by said uniting course the beginning and end of the welt. As soon as 40 the loops *z* of the said course are formed they are withheld upon their needles, for instance in the same manner as above explained in the case of the same needles and the loops *w* during the knitting upon the 45 needles B of the locking fabric X. The fabric X being completed the needles B are restored to operation, the needles A being operated to drop their loops, for instance to cast off all of the loops in the course *x*² prior 50 to supplying yarns to said needles A. This operation may take place independently of the restoration of the needles B then withholding the loops *z* to operation to knit the fabric T, but I prefer to cast off from the 55 A needles in succession after they have completed the fabric X and before the needles B near them are operated in succession to knit the course 32 of the fabric T. The fabric will be retained upon the needles 60 during the interval between casting off and resuming knitting on the needles of the other set by the engagement of the loops *z* with the needles holding them.

The tendency of the fabric X to curl 65 toward the face side holds its last course or

courses, when there is more than one course, or each of its loops, when there is only one course, against the backs of the needles. When the needles A upon which it is knit are retired empty said fabric moves forward into line with or in advance of the line of needles, an effect which secures the laying of the next course, on the needles B, in a position to pick up and hold the ends of the locking fabric forward toward the 70 face side of the whole fabric. The terminal locking loops of course *x*¹ or *x*² are therefore to be found in the finished article each projecting through a sinker wale of the fabric T, as shown in Figs. 3 and 4. The 75 yarns all being of relatively large diameter, compared with the size of the loops shown, it will be seen that the frictional holding of said terminal loops by their penetration through the subsequent fabric is sufficient to 80 prevent any accidental strain from starting the raveling of the locking fabric X. Ordinary strain of use is wholly insufficient to thus cause raveling.

The yarn of course *x*² will extend as at *f* 90 from the last loop of said course to the first loop of the course 32 of the fabric T. Ordinarily the fabric X will be confined to a single course or two courses, although I may knit a part of it as one or more courses 95 and another part of it as two or more courses, depending upon convenience in the order of operating the parts of the instrument of manufacture, as when using an automatic circular machine, for instance of 100 a type the mechanical design of which may make it inconvenient to begin and end all of the operations at the same pair of adjacent needles.

The fabric T, which for some articles may 105 constitute the entire remaining fabric, may for a man's stocking, as illustrated in Fig. 1, extend a sufficient distance to produce substantially the proportions shown. The welt fabric W and the fabric T may be knit of 110 the same yarn and substantially the same length of loop, or if desired the yarn or the stitch length, or both may be changed during the course *x*¹, *x*², or the course 32. Having completed the fabric T, for instance 115 by forming a course 120, Fig. 3, the needles A will be restored to action, in the instance shown, to knit the leg L of the stocking. The fabric following said course 120 may be knit of a different yarn, or with shorter 120 loops, or both. A preferred arrangement of yarns is that indicated in Fig. 3, which is a diagram failing to show the relative proportions of the diameters of yarn for clearness. The top fabric T, indicated in solid black, is knit of heavier yarn than the leg fabric L, the heavy yarn being continued into the leg fabric through at least the first 125 course as at 121, knit upon all of the needles A and B, in order that the heavy yarn may 130

aid in reducing the size of the eyelet-holes h formed in the wales a by the introduction of the needles A at this point. The size of the eyelet hole will be determined by the extent to which the strain downward in wales a is resisted by the sinker-wales between wales b in said first course 121 of the fabric L.

Referring now to Fig. 4, as pointed out above, in some cases it may be inconvenient to begin and end all of the operations of needles A and B upon the same adjacent needles as shown for the preferred fabric of Fig. 3, especially when the knitting is upon a circular automatic knitting machine having as few cam adjusting movements as possible. I may, in order to save adjusting parts, construct a part only of the article in a circumferential sense as shown in Fig. 3, and at the left hand side of Fig. 4, making the remainder of the article as illustrated at the right hand side of Fig. 4. In this case a course 1 may be laid as before and the course 2 may contain the withheld loops w for a part of the periphery, for instance, referring to Fig. 2, throughout the part of the fabric represented by the long butt needles shown in solid black. For a circular stocking knitting machine, this may be substantially one-half the needles corresponding to the instep part of the stocking. At and following the leading low butt needle B' in the direction in which knitting proceeds upon the circle of needles, for instance in the direction opposite to the arrow r of Fig. 2, the short butt needles may be operated to knit a second time without withholding any loops to fasten down the welt, said loops being withheld as shown at w' from the third course in this part of the fabric, i. e. that produced by the short butt needles. The knitting of the welt w proceeds from this point as described above.

When knitting the uniting course Z the operation may again be initiated at the leading short butt needle B' which draws the loop z' , and the said operation may continue through the short butt needles, forming a second course on all of the short-butt needles, as shown at Z^2 . The course x' in this case may begin at the leading long butt needle B² (on the opposite side of the fabric from that shown in Fig. 4), the first course 32 of the fabric T also beginning at the said needle B². The fabric structure comprising the loops w' , the course Z and Z^2 is in this case one course longer at the part of the fabric knit upon the short butt needles than at the part knit upon the long butt needles. This difference is inappreciable in stockings of a usual gage and is of no detriment to the article. It will be understood that for clearness in Figs. 3 and 4 the vertical and lateral relations of the needle loops are much extended.

I have indicated in Fig. 2 by the showing of short jacks j and long jacks j^2 those needles belonging to the series A and the series B which may be rendered alternately operative during the making of the welt, 70 and the making of the attached fabric. For automatic machine manufacture, the needles A may be provided with long jacks, and the machine may be provided with devices causing the needles with short jacks to pass into the knitting cams and knit or under the knitting cams to withhold their loops, whereas the machine may be provided with devices to cause the long jack needles A to pass into the cams to knit, or to be retracted beneath the knitting cams after having their latches cleared through their loops to cast off. When the needles B are retired to hold the loops w the needles A may knit the welt fabric; all of the needles will be operated to 80 knit the uniting course or courses; the needles B may be again retired to hold loops z during knitting of the fabric X on needles A; and the needles A may be retired empty during the knitting of the fabric T on the 90 needles B.

While in each of the illustrative instances above given I have disclosed fabric in which there are the same number of wales a as wales b , alternately arranged, it will be evident without further description that different numbers of wales a and wales b may be employed, so that a wale of one kind would stand between two of the other kind, for instance, or so that recurrent groups of 100 adjacent a wales might alternate with like or different groups of b wales. It will also be evident that the uniting loop fabric of course Z or Z^2 may in some cases be several courses in length, without depriving the fabric of its improved qualities.

What I claim is:

1. A knit fabric having an integral out-turned welt, the welt fabric having needle wales corresponding to sinker wales of the 110 attached fabric.

2. In a knit fabric, a welt, an attached portion, and a uniting course having one needle loop in each needle wale of both said parts.

3. A knit fabric having an integral out-turned welt, the welt fabric having sinker wales corresponding to needle wales of the attached fabric, and needle wales corresponding to sinker wales of the attached fabric.

4. A knit fabric having an integral out-turned welt, said welt and the attached part of said fabric having the same number of wales of knit loops, the welt fabric having sinker wales corresponding to needle wales of the attached fabric, and needle wales corresponding to sinker wales of the attached fabric.

5. A knit article of plain fabric having a 130 welt united thereto by a course containing

- loops in all of the needle wales of the adjacent part of the article, said course having other loops engaging a course of the welt fabric.
5. In a knit fabric, a section having wales terminating in cast-off loops passed through and frictionally held by the sinker wales of adjacent fabric.
6. In a knit fabric, a welt and an attached portion each having therein a certain number of needle-wales, said fabric having at the junction of the welt and the attached fabric a uniting course in which the number of needle loops is the aggregate of said certain numbers.
7. In a knit fabric, an integral welt, united to the attached fabric by a course having needle-loops in wales suppressed in nearby courses, said loops being locked against ravelling by the inclusion of their terminal loops between loops of the attached fabric.
8. In a knit fabric, an integral welt, united thereto by a course containing loops in all the needle wales of the adjacent part of the article, said course also having needle loops continuing those of the last course of the welt fabric; and one or more courses of fabric knit in continuation of said last mentioned loops only.
9. A knit article having a welt united thereto by a course containing loops in all the needle wales of the adjacent part of the article, said course also having needle loops continuing those of the last course of the welt fabric; and one or more courses of fabric knit in continuation of said last mentioned loops only.
10. A knit article having a welt united thereto by a course containing initial loops of all the needle wales of the adjacent part of the article, said course also comprising loops penetrating the last course of welt fabric; and having one or more courses of fabric knit in continuation of said last mentioned loops only.
11. A knit stocking having a body of fabric containing a certain number of needle and sinker wales, a top continuous therewith having fewer needle wales and sinker wales, and an outturned welt having the same number of needle wales and sinker wales as said top, the needle wales of the welt being in line with the sinker wales of the top.
12. A knit stocking having a body of fabric containing a certain number of needle and sinker wales, a top continuous therewith having fewer needle wales and sinker wales, and an integral outturned welt having the same number of needle wales and sinker wales as said top, the needle wales of the welt being in line with the sinker wales of the top, and a uniting course joining said welt and top having knit loops in the needle wales of the top and the welt respectively.
13. The art of knitting welted fabrics on a series of needles comprising knitting fabric for the welt at recurrent needles distributed among the others, during the retention upon intervening needles of withheld loops, thereafter knitting a uniting course engaging said withheld loops and the last course of welt fabric, and thereafter knitting attached fabric at those needles only upon which said withheld loops were retained.
14. The art of knitting welted fabrics on a series of needles comprising forming a course having loops withheld upon recurrent needles; then knitting fabric for a welt at intervening needles; then knitting a uniting course having a needle loop at each of the needles so far employed, and thereafter knitting an extent of fabric at said recurrent needles.
15. The art of knitting welted fabrics on a series of needles comprising forming a course having loops withheld upon recurrent needles; then knitting fabric for a welt at intervening needles; then knitting a uniting course having a needle loop at each of the needles so far employed, then knitting locking fabric at said intervening needles in continuation of loops of said uniting course, and thereafter knitting an extent of fabric at said recurrent needles.
16. The art of knitting welted fabrics on a series of needles comprising forming a course having loops withheld upon recurrent needles; then knitting fabric for a welt at intervening needles; then knitting a uniting course having a needle loop at each of the needles so far employed, then knitting and casting off locking fabric at said intervening needles in continuation of loops of said uniting course and thereafter knitting an extent of fabric at said recurrent needles, said last mentioned operation including engagement of the terminal loops of locking fabric between parts of said extent of fabric.
17. The art of knitting welted fabrics on a series of needles comprising knitting fabric for the welt at recurrent needles distributed among the others, during retention upon intervening needles of withheld loops, thereafter knitting a uniting course engaging said withheld loops and the last course of welt fabric, then knitting one or more courses of locking fabric at the said recurrent needles, casting off said locking courses, permitting the terminal loops to pass forward between the needles at the location of the needles upon which said loops were formed and thereafter knitting attached fabric frictionally engaging said terminal loops at those needles only upon which said withheld loops were retained.
- In testimony whereof, I have signed my name to this specification in the presence of two subscribing witnesses.
